US009816339B2

(12) **United States Patent**
Xu

(10) **Patent No.:** **US 9,816,339 B2**
(45) **Date of Patent:** **Nov. 14, 2017**

(54) **PLUG RECEPTION ASSEMBLY AND
METHOD OF REDUCING RESTRICTION IN
A BOREHOLE**

(71) Applicant: **YingQing Xu**, Tomball, TX (US)

(72) Inventor: **YingQing Xu**, Tomball, TX (US)

(73) Assignee: **BAKER HUGHES, a GE COMPANY,
LLC**, Houston, TX (US)

(57) **ABSTRACT**

A method of reducing restriction in a borehole that is configured for a multizone fracturing operation wherein the borehole has a plurality of plug reception assemblies and each of the plurality of plug reception assemblies includes at least one component configured to disintegrate upon exposure to a selected condition. The method includes exposing the at least one component to a disintegrating environment and facilitating restriction reduction.

**PLUG RECEPTION ASSEMBLY AND
METHOD OF REDUCING RESTRICTION IN
A BOREHOLE**

BACKGROUND

Devices have been available for some time for seatingly receiving a plug within a tubular such as in the downhole hydrocarbon and carbon sequestration industries. These devices necessarily form a restriction within the tubular and typically have features that maintain the devices at fixed positions within the tubular. Though these devices work well for the purpose for which they were designed, the process for removing the restrictions they form, once they are no longer needed, can be costly in both time and money. Removal of such devices from the respective tubular positions can in some cases require running a shifting tool or a cutting tool to the device before it can be disengaged from the tubular. In some cases, this might require an additional dedicated run in the hole with attendant delays and monetary costs. Those who practice in the art will therefore be receptive to devices and methods that overcome the foregoing drawbacks.

BRIEF DESCRIPTION

Disclosed herein is a method of reducing restriction in a borehole that is configured for a multizone fracturing operation, wherein the borehole has a plurality of plug reception assemblies and each of the plurality of plug reception assemblies includes at least one component configured to disintegrate upon exposure to a selected condition. The method includes exposing the at least one component to a disintegrating environment, and facilitating restriction reduction.

Further disclosed herein is a plug reception assembly. The assembly includes at least one component that is disintegratable and facilitates removal of the plug reception assembly as a restriction in a borehole upon disintegration thereof.

BRIEF DESCRIPTION OF THE DRAWINGS

The following descriptions should not be considered limiting in any way. With reference to the accompanying drawings, like elements are numbered alike:

FIG. 1 depicts a cross sectional view of a plug reception assembly disclosed herein.

DETAILED DESCRIPTION

A detailed description of one or more embodiments of the disclosed apparatus and method are presented herein by way of exemplification and not limitation with reference to the Figures.

Referring to FIG. 1, a plug reception assembly disclosed herein is illustrated at 10. The plug reception assembly 10, shown herein as a frac plug, includes a plurality of components. In this embodiment the components include a mandrel 14, a housing 18, a body lock ring 22, at least one slip 28, a cone 32, and an elastic member 36, illustrated herein as a seal. One or more of the components 14, 18, 22, 28, 32 and 36 and subsets thereof are assemblable together to form the plug reception assembly 10.

The plug reception assembly 10 is positionally fixable within a liner or casing 38, or other tubular, or open borehole 40 in an earth formation 44 and is seatingly receptive to a plug 48 run thereagainst. The plug reception assembly 10,

when plugged with one of the plugs 48 can allow pressure to build thereagainst to do work such as fracturing or treating the earth formation 44, or actuating a tool (not shown). A plurality of the plug reception assemblies 10 can be distributed over a length of the borehole 40 so that a plurality of the plugs 48 can be run to sequentially sealingly engage with each of the plug reception assemblies 10. Such a system can be used in a multizone fracturing operation. The plurality of plug reception assemblies 10 can be configured, sized and positioned within the borehole 40 to be seatingly engagable with a plurality of the plugs 48. For example, a smallest of the plugs 48 may be run and engaged with the furthest plug reception assembly 10 while each additional one of the plugs 48 is larger in dimension and engages with the next plug reception assembly 10 positioned adjacently upstream of the previous plug reception assembly 10.

At least one of the components 14, 18, 22, 28, 32, 36 is configured to disintegrate upon being exposed to a selected condition. The selected condition can be a naturally occurring or a created environment. The foregoing allows an operator to remove one or more of the components 14, 18, 22, 28, 32, 36 to thereby facilitate removal of restrictions within the borehole 40 caused by the presence of the plug reception assemblies 10 positioned therewithin. In so doing, the operator can remove the plug reception assemblies 10 after they have served the purpose for which they were employed, without having to run a drill or mill into the borehole 40 to mechanically remove them.

A plurality of the components 14, 18, 22, 28, 32, 36 can be configured to disintegrate in the same target environment. Such an environment can include energy waves such as acoustic waves that can break the components 14, 18, 22, 28, 32, 36 into small pieces, thereby effectively removing the plug reception assembly 10 constructed therefrom. Alternate embodiments of the plug reception assembly 10 can have the components 14, 18, 22, 28, 32, 36 made of metals and metal alloys that are configured to dissolve upon exposure to specific fluids, temperatures and pressures, for example. In some embodiments some of the components 14, 18, 22, 28 and 32 may be rigid members while others, such as the seal 36 can be a non-rigid member such as an elastomer, for example. The fluids can include fluids anticipated to be encountered in a downhole environment such as oil, water, brine and combinations of the foregoing or fluids that are applied to the environment having at least a purpose of dissolving the components 14, 18, 22, 28, 32, 36. As such, for applications wherein the plug reception assembly 10 is employed in the borehole 40 such as during a hydrocarbon recovery or a carbon dioxide sequestration operation, for example, the dissolution of the components 14, 18, 22, 28, 32, 36 can be initiated by entry into the borehole 40. Alternately, dissolution can be initiated after exposing the plug reception assembly 10 to a selected fluid that is pumped to the location of the plug reception assembly 10. Fluids such as acids and bases that may not occur naturally in the borehole 40 can allow additional control over timing of dissolution since the dissolution would not begin until the selected fluid is introduced to the location of the plug reception assembly 10. Relying on pumping the selected fluid before disintegration occurs provides additional control since a subset of a whole set of the plug reception assemblies 10 can be selectively exposed to the selected fluid at a desired time.

Both the mandrel 14 and the housing 18 are in operable engagement with the body lock ring 22. The operable engagement being through a ratcheting arrangement. The body lock ring 22 has radially outward facing teeth 52 that

engage with radially inwardly facing teeth **54** on the housing **18**. The body lock ring **22** also has radially inwardly facing teeth **56** that engage with radially outwardly facing teeth **58** on the mandrel **14**. The body lock ring **22** is C shaped due to a longitudinal opening (not visible in the FIGURE) that extends longitudinally through the body lock ring **22**. This allows the body lock ring **22** to flex which action changes a radial size of the body lock ring **22** to thereby allow the teeth **56** thereon to ratchet relative to the teeth **58** when the mandrel **14** is pushed longitudinally toward the housing **18**. This ratcheting engagement, while allowing longitudinal movement of the mandrel **14** towards the housing **18** prevents movement of the mandrel **14** in a longitudinal direction away from the housing **18** thereby discouraging unsetting of the plug reception assembly **10** from its position within the borehole **40**. Disintegration of one more of the mandrel **14**, the housing **18** and the body lock ring **22** can defeat the ratcheting engagement of the teeth **52, 54, 56, 58**.

While the invention has been described with reference to an exemplary embodiment or embodiments, it will be understood by those skilled in the art that various changes may be made and equivalents may be substituted for elements thereof without departing from the scope of the invention. In addition, many modifications may be made to adapt a particular situation or material to the teachings of the invention without departing from the essential scope thereof. Therefore, it is intended that the invention not be limited to the particular embodiment disclosed as the best mode contemplated for carrying out this invention, but that the invention will include all embodiments falling within the scope of the claims. Also, in the drawings and the description, there have been disclosed exemplary embodiments of the invention and, although specific terms may have been employed, they are unless otherwise stated used in a generic and descriptive sense only and not for purposes of limitation, the scope of the invention therefore not being so limited. Moreover, the use of the terms first, second, etc. do not denote any order or importance, but rather the terms first, second, etc. are used to distinguish one element from another. Furthermore, the use of the terms a, an, etc. do not denote a limitation of quantity, but rather denote the presence of at least one of the referenced item.

What is claimed is:

1. A method of reducing restriction in a borehole, the borehole having a plug reception assembly having one longitudinal end and another longitudinal end and including:

a mandrel providing a flowpath, the mandrel configured to receive a plug to block flow through the flowpath in a downhole direction;

an elastic member forming a portion of a radially exterior surface of each respective plug reception assembly, the elastic member having one longitudinal end and another longitudinal end;

only a single set of slips arranged to maintain the plug reception assembly in anchored relation to a borehole, the single set of slips disposed between the one longitudinal end of the plug reception assembly and the one longitudinal end of the elastic member, and the plug reception assembly being free of slips between the other longitudinal end of the plug reception assembly and the other longitudinal end of the elastic member; and

at least one component of the plug reception assembly being disintegratable by an acoustic wave, the at least one component being one that upon disintegration facilitates removal of the plug reception assembly as a restriction in the borehole, the method comprising:

exposing the at least one component to the acoustic wave within which the at least one component is configured to disintegrate; and facilitating restriction reduction.

5 2. The method of claim 1, further comprising disintegrating substantially all rigid components within the plug reception assembly.

3. The method of claim 1, wherein the plug reception assembly is a frac plug.

10 4. A method of reducing restriction in a borehole, the borehole having a plug reception assembly, the plug reception assembly defining a flowpath and arranged to receive a plug to block flow through the flowpath in a downhole direction, the plug reception assembly including at least one slip to independently maintain the plug reception assembly in anchored relation to the borehole, the plug reception assembly including at least one component configured to dissolve or disintegrate upon exposure to a selected condition, the method comprising:

15 exposing the at least one component to the selected condition to dissolve or disintegrate the at least one component; and facilitating restriction reduction;

20 wherein the at least one component is at least one portion of a locking arrangement between a housing and a mandrel of the plug reception assembly, and further comprising defeating the arrangement upon exposing the arrangement to the selected condition, wherein the arrangement maintains the at least one slip of the plug reception assembly in fixed position along the borehole prior to dissolving or disintegrating the at least one portion of the arrangement.

25 5. The method of claim 4, wherein the at least one portion of the arrangement includes a body lock ring disposed radially between the mandrel and the housing, the body lock ring having inwardly and outwardly facing teeth that ratchet with teeth of the mandrel and teeth of the housing, wherein disintegration or dissolution of the body lock ring defeats a ratcheting engagement between the mandrel and the housing.

30 6. The method of claim 4, wherein the arrangement allows longitudinal movement of the mandrel towards the housing, and prevents movement of the mandrel in a longitudinal direction away from the housing.

35 7. The method of claim 4, wherein the arrangement is a ratcheting arrangement.

8. A plug reception assembly having one longitudinal end and another longitudinal end, the plug reception assembly comprising:

40 a mandrel providing a flowpath, the mandrel configured to receive a plug to block flow through the flowpath in a downhole direction;

an elastic member forming a portion of a radially exterior surface of the plug reception assembly, the elastic member having one longitudinal end and another longitudinal end;

45 only a single set of slips arranged to maintain the plug reception assembly in anchored relation to a borehole, the single set of slips disposed between the one longitudinal end of the plug reception assembly and the one longitudinal end of the elastic member, and the plug reception assembly being free of slips between the other longitudinal end of the plug reception assembly and the other longitudinal end of the elastic member; and

50 at least one component of the plug reception assembly being configured to disintegrate upon exposure to the

acoustic wave, the at least one component being one that upon disintegration facilitates removal of the plug reception assembly as a restriction in the borehole.

9. The plug reception assembly of claim 8, wherein the at least one component is a plurality of rigid components configured to maintain the plug reception assembly in sealed relation to the borehole.

10. The plug reception assembly of claim 8, further comprising only a single slip-actuating cone for actuating the single set of slips.

11. The plug reception assembly of claim 8, wherein the one longitudinal end of the plug reception assembly is a downhole end of the plug reception assembly, and the one longitudinal end of the elastic member is a downhole end of the elastic member.

12. The plug reception assembly of claim 8, wherein a longitudinal length between the one end of the elastic member and the one end of the plug reception assembly is greater than a longitudinal length between the other end of the elastic member and the other end of the plug reception assembly.

13. The plug reception assembly of claim 8, further comprising a housing, the housing additionally providing the flow path, the housing and the mandrel extending along a radially interior surface of the plug reception assembly, wherein longitudinal movement of the mandrel relative to the housing reduces a longitudinal length of the plug reception assembly from the one end of the plug reception assembly to the other end of the plug reception assembly.

14. The plug reception assembly of claim 13, further comprising a locking arrangement between the mandrel and the housing.

15. The plug reception assembly of claim 13, wherein the elastic member is positioned radially outwardly of the mandrel, and the single set of slips is disposed radially outwardly of the housing.

16. The plug reception assembly of claim 15, further comprising a cone disposed radially outwardly of both the mandrel and the housing.

17. A plug reception assembly, comprising:
a mandrel providing a flowpath, the mandrel configured to

receive a plug to block flow through the flowpath in a downhole direction;

at least one slip arranged to maintain the plug reception assembly in anchored relation to a borehole; and

at least one component of the plug reception assembly being disintegrable or dissolvable upon exposure to a selected condition, the at least one component being one that upon disintegration or dissolution facilitates removal of the plug reception assembly as a restriction in the borehole;

wherein the at least one component is at least one portion of a locking arrangement between a housing and the mandrel of the plug reception assembly, wherein the arrangement maintains the at least one slip of the plug reception assembly in a fixed position along the borehole prior to disintegrating or dissolving the portion of the arrangement.

18. The plug reception assembly of claim 17, wherein the at least one component is a metal alloy.

19. The plug reception assembly of claim 17 wherein the plug reception assembly is a frac plug.

20. The plug reception assembly of claim 17, wherein the at least one portion of the arrangement includes a body lock ring disposed radially between the mandrel and the housing, the body lock ring having inwardly and outwardly facing teeth that ratchet with teeth of the mandrel and teeth of the housing, wherein disintegration or dissolution of the body lock ring defeats a ratcheting engagement between the mandrel and the housing.

21. The plug reception assembly of claim 17, wherein the plug to block flow through the flowpath in a downhole direction is a first plug having a first size, and the flowpath extends from a first end to a second end of the plug reception assembly, the flowpath configured to enable passage of a second plug from a location uphole of the plug reception assembly to a location downhole of the plug reception assembly, the second plug having a second size smaller than the first size.

22. The plug reception assembly of claim 17, wherein the arrangement allows longitudinal movement of the mandrel towards the housing, and prevents movement of the mandrel in a longitudinal direction away from the housing.

23. The plug reception assembly of claim 17, wherein the arrangement is a ratcheting arrangement.

24. A plug reception assembly having one longitudinal end and another longitudinal end, the plug reception assembly comprising:

a mandrel providing a flowpath, the mandrel configured to receive a plug to block flow through the flowpath in a downhole direction;

an elastic member forming a portion of a radially exterior surface of the plug reception assembly, the elastic member having one longitudinal end and another longitudinal end;

only a single set of slips arranged to maintain the plug reception assembly in anchored relation to a borehole, the single set of slips disposed between the one longitudinal end of the plug reception assembly and the one longitudinal end of the elastic member, and the plug reception assembly being free of slips between the other longitudinal end of the plug reception assembly and the other longitudinal end of the elastic member; a housing, the housing additionally providing the flow path, the housing and the mandrel extending along a radially interior surface of the plug reception assembly, wherein longitudinal movement of the mandrel relative to the housing reduces a longitudinal length of the plug reception assembly from the one end of the plug reception assembly to the other end of the plug reception assembly; and

a locking arrangement between the mandrel and the housing, the arrangement allows longitudinal movement of the mandrel towards the housing, and prevents movement of the mandrel in a longitudinal direction away from the housing.

25. The plug reception assembly of claim 24, wherein at least a portion of the locking arrangement is disintegrable or dissolvable upon exposure to a selected condition.
